SPRING OPERATED TOY

Sammy Wechsler, New York, N. Y.

Application December 11, 1947, Serial No. 791,118

4 Claims. (Cl. 46—208)

1

This invention relates to spring operated toys wherein a spring is compressed and more particularly to that type of such toys which are operated by a compressed spring which, when released, will propel the toy in a forward direction.

An object of the invention is to provide a toy of the class described wherein the mounting for the spring is of simplified construction and readily adapted for use with toys having plastic bodies.

Another object is the provision of a toy of the class described in which a simple and efficient release mechanism is provided under the control of the user for releasing the toy to the operation of the spring.

A further object is the provision of a toy of the class described which is attractive in appearance and in which the propelling mechanism has a minimum of parts that are not easily damaged by children.

Other objects and advantages will be apparent from the accompanying specification and drawings where the invention is shown applied to a toy automobile.

It will be understood however, that this invention is applicable to any type of toy, for example, an airplane, or to any other toy which it is desired to either propel along the ground or project into the air under the power of a spring, as hereinafter described.

In the accompanying drawings:

Figure 1 is a horizontal view partly in section of a toy automobile embodying the invention, with the spring in extended or released position;

Figure 2 is a view partly in section of the containing tube for the spring, the latter being shown in compressed position;

Figure 3 is a detail view partly in section of a modified form of the locking mechanism for the spring; and

Figure 4 is a rear view showing a modified form of spring holder as used on a slightly different type of automobile body than that shown in Figure 1.

Referring to Figure 1, the numeral 10 generally denotes the body of a toy automobile which may be made of metal, plastic or any other suitable material. By way of illustration, it will be assumed that a plastic body is shown and this is broken away as indicated in the figure in order to show the mounting for the propelling spring hereinafter described.

Such plastic bodies for toy automobiles are usually die cast or injection molded and in the embodiment shown in the drawing, such a body

2

is molded with horizontal transverse ribs 11 and 12 therein and the body is provided at its rear end with a tube receiving aperture 13.

A tube 14 made of any suitable material, for example rolled up out of tin, is pushed into the opening 13 and the inner end of said tube is supported between the ribs 11 and 12.

A normally expanded spring 15 is placed within the tube and the inner end of this spring is suitably formed into a hook or eye 16 to receive a pin 17 which may be inserted from the bottom of the body as shown in Figure 1.

This pin passes through the rib 12, through the wall of the tube 14 and the eye 16 of the spring 15 and terminates in the rib 11 thereby securing the tube to the body 10 and the spring within the tube, the pin performing a double function in this respect.

If now the automobile is placed on the ground 20 and held with one hand while a rod 18 is inserted into the tube 14 with the other hand, the spring 15 will be compressed to the position shown in Figure 2, and when it reaches a suitable compressed position, a latch 19 in the rod will enter 25 an aperture 20 in the body and engage the inner wall of said aperture, or the latch 19 will enter the enlarged outer end 21 of the tube 14. In either event, the rod 18 will hold the spring 15 under compression.

If now the automobile is released from the hand while the rod 18 is held by the user, and the latch 19 is depressed as indicated by the thumb 22, Figure 2, the automobile will be released from the rod 18, spring 15 will suddenly expand, driving the automobile forward a considerable distance. If, instead of an automobile a toy airplane is used, the airplane will be projected into the air by the force of the spring.

It will be seen from the foregoing that the inner end of the latch 19, Figure 1, engages the body of the automobile whereas in Figure 2, the inner end of the latch engages the outer end of tube 14, which is shaped to receive it.

The latter construction eliminates the necessity of the opening 20 in the body which is desirable in some instances, whereas the construction in Figure 2 ensures a very definite mutual relationship between the tube 14 and the rod 18 and affords a somewhat more precise latch mechanism, as the latch operation is a metal to metal one instead of being metal to plastic as that shown in connection with Figure 1.

In Figure 3 is shown a modified form of latch mechanism. Here the tube 14 has an opening 23 55 in its side wall.

A latch 24 is welded or otherwise suitably secured to the tube 14. This latch can be a piece of spring wire and it has a nose portion 25 extending into the opening 23 and an outwardly extending tip portion 26 which may extend outwardly below the body 10 of the automobile.

The rod 18 has a circular notch 27 therein and the inner end of the rod is rounded as shown at 28.

If now the rod having the rounded end 28 is inserted into the tube 14, the rounded end 28 will engage the nose portion 25 of the spring 24 and depress same and the rod will ride past the nose 25 until said nose enters the notch 27, whereupon the nose will enter the notch, as shown in Figure 3, thereby locking the rod 18 with spring 15 in its compressed position as shown in Figure 2.

If now the outer end of the rod 18 is held in the hand and the outer end 26 of the latch 24 is slightly depressed, the vehicle will be released to the action of spring 15 and will be projected forward away from the rod.

While the invention has been described wherein the spring is mounted within the vehicle or object to be moved, it will be understood that the relative positions of spring 15 and rod 18 may be reversed in a manner that will be obvious and that the inventive concept resides in interposing the spring between the object to be moved and a member to be held in the hand of the user, together with the provision of means for releasing the object to the tension of the spring.

Referring to Figure 4, a modified form of spring holder is shown replacing the tube 14 shown in the preceding figures.

In Figure 4 the body of the automobile is indicated by the numeral 29, but obviously this may be of any type such as that shown in Figure 1.

Secured to the bottom of the body in a suitable manner such as by the ordinary drive pins 30, are the bottom plates 31, 32 which may cover the entire bottom of the automobile or only so much of it as may be necessary.

The plates 31, 32 are shaped so as to form, when placed together, a tube or bore 33 which forms the housing for the spring 15 and acts exactly the same as the tube 14 in Figures 1 to 3.

The spring 15 is held in the bore 33 in any suitable manner as, for example, anchoring the loop 16 of the spring through a hole in the side wall of the bore, or the end of the bore can be pinched together to close it at the forward end with a loop of the spring in the pinch.

While in connection with Figures 1 and 2 the latch 19 is shown for the sake of simplicity and convenience as a piece of spring wire riveted or otherwise secured to the rod or compression member 18, it will be obvious that this latch could be

formed by the outer end of the rod turned to form an open eye so that the rod and latch is formed in one piece of metal in a manner that will be obvious.

5. What is claimed is:

1. In a toy, in combination, a body forming a chamber, a compression member to be held in the hand and to be associated with said body to compress a spring, said member being separable from said body a normally expanded spring positioned within said chamber in said body extending between said body and said member, and latching means secured to said member and engaging the wall of said body at the rear end thereof for holding said member partly within said body to compress said spring, said means having a resilient part lying outside said body and extending freely toward said body to be operated by manual pressure applied thereto when said member is held in the hand to release said body to the action of said spring, to cause said body to withdraw from said member while the latter is held in the hand as aforesaid.

2. The combination as claimed in claim 1 wherein said latching means is resiliently secured to said compression member and engages said body when said member is associated therewith to compress said spring.

3. The combination as claimed in claim 1 including a tube extending longitudinally of the body and wherein said spring is mounted within said tube and where said compression member comprises a rod adapted to enter said tube to compress said spring therein.

4. The combination of a body having a rib therein, a tube secured to said rib and extending lengthwise of said body and through the rear end thereof, a spring within said tube and having its forward end fixed relative to said body, a compression member adapted to be forced into said tube to compress the spring therein and a resilient latch secured to said member and adapted to engage said body whereby said member may be held in said tube against the pressure of said spring.
